POWER LAWN EDGER

Fred J. Machovec, Pasadena, Calif.

Application September 6, 1955, Serial No. 37,799

Term of patent 14 years

(Cl. D40—1)

FIG. 2.

FIG. 1.

FIG. 4.

FIG. 5.

Fig. 1 is a left side elevational view of a power lawn edger showing my new design;

Fig. 2 is a plan view thereof;

Fig. 3 is a front elevational view thereof;

Fig. 4 is a right side elevational view thereof; and

Fig. 5 is a rear perspective view thereof taken from the left side.

The dominant features of my new design are shown in the drawing, in solid lines.

I claim:

The ornamental design for a power lawn edger, substantially as shown and described.
